(57) **CLAIM**

We claim the ornamental design for a garment, as shown and described.

DESCRIPTION

FIG. 1 is a front perspective view of a garment, such as a hoodie.

FIG. 2 is a rear perspective view of the garment shown in FIG. 1.

FIG. 3 is a front view of the garment shown in FIG. 1.

FIG. 4 is a rear view of the garment shown in FIG. 1.

FIG. 5 is a right side view of the garment shown in FIG. 1.

FIG. 6 is a left side view of the garment shown in FIG. 1.

FIG. 7 is a front perspective view of a garment, such as a hoodie.

FIG. 8 is a rear perspective view of the garment shown in FIG. 7.

FIG. 9 is a front view of the garment shown in FIG. 7.

FIG. 10 is a rear view of the garment shown in FIG. 7.

FIG. 11 is a right side view of the garment shown in FIG. 7; and,

FIG. 12 is a left side view of the garment shown in FIG. 7. The stitching shown in broken lines forms a part of the claimed design.

In FIGS. 1-6, the crosshatching represents a texture of the material forming a part of the claimed design. In FIGS. 7-12, stippling and straight-line surface shading represent contrast in materials.

1 Claim, 12 Drawing Sheets
